US0D1114280S

(12) **United States Design Patent** (10) **Patent No.:** **US D1,114,280 S**
(45) **Date of Patent:** **** Feb. 17, 2026**

(54) **APPARATUS FOR THERMOTHERAPY**

(71) Applicant: **Dermapharm AG**, Grünwald (DE)

(72) Inventor: **Alexander Grimm**, Halle/Saale (DE)

(73) Assignee: **Dermapharm AG**, Grünwald (DE)

(**) Term: **15 Years**

(21) Appl. No.: **29/914,418**

(22) Filed: **Oct. 17, 2023**

(30) **Foreign Application Priority Data**

Apr. 19, 2023 (EM) 015018638

(57) **CLAIM**

The ornamental design for an apparatus for thermotherapy, as shown and described.

DESCRIPTION

FIG. 1 is a top plan view of an apparatus for thermotherapy;
FIG. 2 is a bottom plan view thereof;
FIG. 3 is a front elevation view thereof;
FIG. 4 is a rear elevation view thereof;
FIG. 5 is a left side view thereof;
FIG. 6 is a right side view thereof;
FIG. 7 is a top, front, left right perspective view of the
apparatus for thermotherapy; and,
FIG. 8 is a top, rear, left side perspective view thereof.
The short dash-short dash broken lines depict portions of the
apparatus for thermotherapy that form no part of the claimed
design.

1 Claim, 7 Drawing Sheets
